(57) **CLAIM**

The ornamental design for a handle for an optical device, medical device, or the like, as shown and described.

DESCRIPTION

FIG. 1 is a perspective view of a handle for an optical device, medical device, or the like showing my new design;

FIG. 2 is another perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof;

FIG. 9 is a perspective view of another embodiment of a handle for an optical device, medical device, or the like showing my new design;

FIG. 10 is another perspective view thereof;

FIG. 11 is a front elevation view thereof;

FIG. 12 is a rear elevation view thereof;

FIG. 13 is a right side elevation view thereof;

FIG. 14 is a left side elevation view thereof;

FIG. 15 is a top plan view thereof; and,

FIG. 16 is a bottom plan view thereof.

The broken dash lines shown in the figures represent portions of the handle for an optical device, medical device, or the like that form no part of the claimed design. The broken dash dot line represents boundaries to the claimed design and forms no part of the claimed design.
